Primary Examiner — Mitchell I. Siegel*(74) Attorney, Agent, or Firm* — Stephen J. Stark; Miller & Martin PLLC(57) **CLAIM**

The ornamental design for an animal head, as is shown and described herein.

DESCRIPTION

FIG. 1 is a left perspective view of the animal head;
 FIG. 2 is a right perspective view thereof;
 FIG. 3 is a top plan view thereof;
 FIG. 4 is a bottom plan view thereof;
 FIG. 5 is a right side elevational view thereof, the left side being a mirror image thereof;
 FIG. 6 is a rear elevational view thereof; and,
 FIG. 7 is a front elevational view thereof.
 The broken line portion of the figure drawings is included to show portions of the article that forms no part of the claimed design.

1 Claim, 5 Drawing Sheets(56)
